UNITED STATES PATENT OFFICE

2,479,582

PROJECTILE FUSE

James F. McCaslin, Cleveland, Ohio

Application May 7, 1945, Serial No. 592,434

8 Claims. (Cl. 102—81)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to an improved safety means for projectile fuzes of the types employed in rifle grenades, rockets, and similar projectiles.

The primary object of the present invention is to provide a fuze having a delay arming means actuated by the gases propelling the projectile for arming the fuze during acceleration of the projectile to eliminate the danger of casual displacement of the firing pin after removal of the safety pin and before firing of the projectile, which can readily occur if the projectile is dropped from an elevation of approximately two feet.

Still another object of the invention is to utilize the annular groove normally provided in firing pins of such fuzes for receiving a retaining element which is retracted out of engagement with said groove by means actuated by the propelling gases.

Other objects and advantages of the invention will hereinafter become more fully apparent from the following description of the drawings, which illustrate the preferred embodiments thereof, and wherein:

Figure 1 is a longitudinal, substantially central sectional view of a portion of a rifle grenade and with the invention shown incorporated therein;

Figure 2 is a fragmentary sectional view, similar to Figure 1, and showing the safety means in a retracting position, for arming the fuze;

Figures 3, 4, and 5 are cross sectional views of portions of the projectile taken substantially along planes as indicated by the lines 3—3, 4—4 and 5—5, respectively, of Figure 1;

Figure 6 is a longitudinal, substantially central sectional view of the firing pin shown detached from the fuze;

Figure 7 is a fragmentary sectional view, similar to Figure 1 of a slightly modified form of the fuze;

Figure 8 is a top plan view of one element of the invention shown detached;

Figure 9 is an enlarged longitudinal sectional view of another form of the invention, especially adapted for use in rocket type projectiles;

Figure 10 is an enlarged cross sectional view of the fuze taken substantially along a plane as indicated by the line 10—10 of Figure 9;

Figure 11 is a side elevational view of one element of the invention as shown in Figure 10;

2

Figure 12 is a bottom plan view of the same; and

Figure 13 is an elevational view of another part of the invention.

5 Referring more particularly to the drawings, wherein like reference characters designate like and corresponding parts throughout the several views, and referring particularly to Figures 1 to 6 and 8, 15 designates generally the rear portion 10 of a rifle grenade including a launcher tube 16, a tail fin assembly 17 and a fuze, designated generally 18.

The fuze 18 includes a housing 19 having a restricted forwardly extending nipple 20 which is externally threaded to engage a burster charge, not shown, and is internally threaded to receive a primer detonator holder 21. The housing 19 is provided with an axially disposed bore 22 which extends to adjacent the rear thereof and which 15 opens into the nipple 20 and is, therefore, in communication with the holder 21. A firing pin 23 is slidably disposed in the bore 22 and is provided with a tapered forward projection 24 which is aligned with an opening in the rear end of the 20 holder 21 for receiving said projection, when the firing pin is projected forwardly and into engagement with a primer detonator, not shown, contained in the holder 21 and which is detonated thereby, in a conventional manner. A magnet 25 25 is seated in and projects from the rear end of the firing pin 23, and the rear end portion, at least, of the housing 19 is formed of a metal which is attracted by the magnet 23 so that said magnet will function to normally retain the firing pin 23 30 in a fully retracted, rearmost position within the bore 22, as illustrated in Figure 1. The body portion of the firing pin 23 is provided with an outwardly opening annular groove 26, intermediate of its ends, for receiving a conventional safety pin 27, which is removably anchored in the 35 housing 19, for holding the firing pin in its retracted position. The parts previously described, except the magnet 25, are all conventional.

40 45 The gas actuated safety device comprising the invention, designated 28, includes a sleeve or ring 29 which is disposed in the tube 16 and directly behind the housing 19 and which is suitably fixed therein. The sleeve 29, at its rear edge, is provided with an inturned annular flange 30, and as seen in Figure 5, a portion of the sleeve 29 is split and bent upwardly to form wings or lugs 31. The inner or rear edges of said lugs 31 are inclined forwardly and upwardly in a direction away 50 55 from the flange 30, for a purpose which will here-

inafter become apparent. A disk 32 is loosely disposed in the sleeve 29 and is of sufficient diameter so that its peripheral portion will bear against the inner or forward side of the flange 30. The central portion of the disk 32 is dished rearwardly and said dished portion is disposed in the opening formed by the annular flange 30 and the outer side thereof is disposed substantially flush with the outer side of said flange as clearly shown upon Fig. 1. When the disk 32 is thus disposed, a portion thereof is arranged between the inclined edges of the lugs 31 and a part of the flange 30.

The housing 19 is provided with a radial bore 33 which opens outwardly thereof at one of its ends and which has its opposite end opening into the bore 22 and communicating with the groove 26, when firing pin 23 is in a fully retracted position. A retaining element or detent 34 is reciprocally disposed in the bore 33 and is provided with a bifurcated inner end 35 which extends into the groove 26 when the detent 34 is in a projected, operative position, as seen in Figure 1. The apex 36 of the bifurcated portion 35 is inclined forwardly and downwardly, as best seen in Figure 2. The housing 19 is provided with a longitudinally extending bore 37 which opens outwardly of the rear end thereof and which intersects the bore 33 adjacent its forward end. A rod or plunger 38 is reciprocally disposed in the bore 37 and the rear end thereof normally projects from the rear face of the housing 19 and bears against a part of the disk 32 which is substantially diametrically opposed to the portion thereof which is in proximity to the lugs 31. As best seen in Figure 8, the opposite, forward end of the plunger 38 is provided with a restricted extension 39, the horizontal width of which is substantially less than the diameter of the plunger 38. The vertical width of the extension 39, adjacent to plunger 38, is approximately equal to the diameter of the rod 38, and therebeyond, the upper surface of the extension 39 is bevelled to form a cam surface 40, which is disposed at substantially the same angle as the inclined surface 36 against which a portion of surface 40 normally engages, as seen in Figure 1. The forward end of the extension 39 is rounded slightly to enable it to more readily engage under the surface 36.

Assuming that the safety pin 21 has been removed, the fuze 18 will still be retained in a safe or disarmed condition by the furcations 35 engaging in the groove 26. When the projectile 15 is fired from a rifle grenade launcher in a conventional manner, the expanding gases of the propelling cartridge will impinge against the disk 32 in the course of propelling the projectile from the launcher and in so doing will force the disk 32 forwardly relatively to the sleeve 29. The lugs 31 will provide a fulcrum for disk 32 upon which the disk will rock from its position in Figure 1 to its position in Figure 2. This rocking movement of the disk 32 will project the plunger or rod 38 forwardly in the bore 37 and by camming engagement of the surfaces 36 and 40 the retaining member 34 will be cammed outwardly relatively to the bore 33 and out of engagement with the groove 26 to release the firing pin 23 and thereby arm the fuze 18. After release of the firing pin by retaining member 34, said firing pin will be held in its retracted position by the magnet 25 until impact of the projectile with a target, at which time inertia will overcome the power of the magnet 25, thus releasing the firing pin for unretarded forward movement in the

bore 22 to cause it to strike and detonate the primer, not shown, contained in holder 21 which will in turn detonate the burster charge, not shown. To prevent casual displacement of the retaining member 34, a shear wire 41 extends through a portion of the housing 19 and through an opening in the retaining member 34. Said wire 41 is sheared when retaining member 34 is forced outwardly by forward movement of the plunger 38. As seen in Figure 4, housing 19 is provided with longitudinal kerfs 42 to facilitate insertion of the wire 41.

The embodiment of the invention shown in Figure 7 differs from the form, previously described, only in that the magnet 25 is omitted, and in lieu thereof a helical spring 43 is disposed between the forward end of the body portion of the firing pin 23 and the primer holder 21 and functions as a creep spring to retain the firing pin 23 in a retracted position until impact of the projectile with its target.

In the embodiment of the invention disclosed in Figures 9-13, 44 designates generally a portion of a projectile of the rocket type including a tube 45 forming a portion of the motor chamber thereof. A fuze, designated generally 46, includes a housing 47, the rear end of which is suitably anchored in the forward end of the tube or motor chamber 45 and which contains a firing pin 48 corresponding to the firing pin 23 and held by a manually removable safety pin 49, in the same manner as the safety pin 21.

An obturating piston 50 is reciprocally disposed in the enlarged forward part of the tube 45. The bore of the tube 45 is restricted behind piston 50 to form a forwardly facing shoulder 51 between which and the housing 47 the piston 50 is slidably disposed. The housing 47, as best seen in Figure 10, is provided with a slot 52 which opens outwardly of its periphery and which is provided with a restricted opening 53 which communicates with the firing pin bore and with the annular groove 54 of the firing pin, when in its fully retracted position. In lieu of the retaining element 34, the fuze 46 is provided with a strand of wire 55, one end of which is anchored in a recess 56 of the housing 47 and which opens into the slot 52. The opposite end of the wire 55, after the first-mentioned end has been anchored in the recess 56, is bent into substantially hooked shaped form as seen at 57 and a terminal or bill 58 thereof projects through the opening 53 and into the groove 54. The housing 47 is provided with a longitudinally extending bore 59 which intersects the transversely disposed slot 52 and in which is reciprocally mounted a plunger 60. The rear end of the plunger 60 projects from the rear face of the housing 47 and terminates in a neck portion 61 which extends through the head of the piston 50 and is suitably spread or enlarged therebeyond to provide a head 62 which engages the inner side of the piston head. The opposite, forward end of the rod or plunger 60 is tapered to form a conical point 63, the bottom part of which forms an elongation of the bottom portion of the plunger 60. The forward end of the cone 63 engages under the arcuate inner side 64 of the hook 57.

Assuming that the safety pin 49 had been removed, and the projectile 44 is fired from suitable launching means, not shown, the propelling gases thereof will impinge against the inner or rear side of the head of the piston 50 as the projectile is accelerated to thus drive the piston 50 forwardly against the rear end of the housing

47. This will cause the conical portion 63 to move through the inner portion of the hook 57 to cam or wedge the terminal 58 thereof out of engagement with the groove 54, through the camming engagement of the conical portion 63 with the arcuate portion 64 of the hook 57. As a result, the firing pin 48 will be released to be actuated upon impact of the projectile 44 with a target in the same manner that the firing pin 23 is projected by inertia, as previously explained. The strand or rod 55 is bent into the form shown in Figure 10 upon being applied to the housing 47 and in Figure 13 is shown in its initial shape before application to the housing.

Various other modifications and changes are 15 likewise contemplated and may obviously be resorted to, without departing from the spirit and scope of the invention as hereinafter defined by the appended claims, as only preferred embodiments thereof have been disclosed.

I claim:

1. In a fuze for a rifle grenade, a housing having a central axial bore opening forwardly through said housing, a firing pin slidably fitting said bore and movable therein from a safe to a firing position, a detent movably mounted in a first radial hole in said housing opening into said bore, the inner end of said detent normally engaging said firing pin to retain the same in safe position, a tube, said housing fitting and being rigidly secured to the forward end of said tube, a release rod slidably mounted in a second hole in said housing, said second hole being parallel with and laterally offset from said bore and opening through the rear face of said housing and intersecting said first hole, a piston movable in said tube and operable to slide said rod from a first to a second position in response to gas pressure incident to firing of said grenade, said detent and said rod having interengaging cam surfaces effective to move said detent radially outwardly out of engagement with said firing pin when said rod is moved to second position.

2. In a fuze for a rifle grenade, a housing having a central axial bore opening forwardly through said housing, a firing pin having a circumferential channel and slidably fitting said bore, a detent movably mounted in a first radial hole in said housing opening into said bore, the inner end of said detent normally entering said channel to retain said firing pin in safe position, a tube, said housing fitting and being secured within the forward end of said tube, a release rod slidably mounted in a second hole in said housing, said second hole being laterally offset from and parallel with said bore, opening through the rear face of said housing and intersecting said first hole, a piston movable in said tube and operable to slide said rod from a first to a second position in response to gas pressure incident to firing of said grenade, said detent and said rod having interengaging cam surfaces effective to move said detent out of said channel when said rod is moved to second position.

3. A fuze for projectiles of the rifle grenade and rocket type, comprising, a piston movably disposed in a projectile and arranged to be actuated by the propelling gases thereof, said projectile having a fuze including a housing and a firing pin slidably disposed therein, said firing pin having an outwardly opening recess formed therein, a retaining member slidably mounted in an aperture in the housing and normally engaging in said firing pin recess to retain said firing

pin in safe position, means actuated by the piston and engaging the retaining member for moving the retaining member out of engagement with the firing pin when the piston is actuated by the propelling gases, and a sleeve having an annular inturned flange at one end thereof in which the piston is disposed, said piston constituting a disk the peripheral portion of which engages against said flange and the remaining portion of which substantially closes the opening formed by the flange.

4. A fuze for projectiles of the rifle grenade and rocket type, comprising, a piston movably disposed in a projectile and arranged to be actuated by the propelling gases thereof, said projectile having a fuze including a housing and a firing pin slidably disposed therein, said firing pin having an outwardly opening recess formed therein, a retaining member slidably mounted in an aperture in the housing and normally engaging within said firing pin recess for retaining the firing pin in a safe position, means actuated by said piston and engaging said retaining member for moving the retaining member out of engagement with the firing pin when the piston is actuated by the propelling gases, and a sleeve having an annular inturned flange at one end thereof in which the piston is disposed, said piston comprising a disk the peripheral portion of which engages against said flange and the remaining portion of which substantially closes the opening formed by the flange, said disk being dished, the dished portion extending into the flange opening and substantially filling the same.

5. A fuze for projectiles of the rifle grenade and rocket type comprising a piston movably disposed in a projectile and arranged to be actuated by the propelling gases thereof, said projectile having a fuze including a housing and a firing pin slidably disposed therein, said firing pin having an outwardly opening recess formed therein, a retaining member slidably mounted in an aperture in the housing and normally engaging within said firing pin recess for retaining said firing pin in a safe position, means actuated by the piston and engaging said retaining member for moving the retaining member out of engagement with the firing pin when the piston is actuated by the propelling gases, and a sleeve having an annular inturned flange at one end thereof in which the piston is disposed, said piston constituting a disk the peripheral portion of which engages against said flange and the remaining portion of which substantially closes the opening formed by said flange, said sleeve having an inwardly projecting lug spaced from the flange and against which a portion of the disk bears to cause said disk to rock in the sleeve and on the lug as a fulcrum when actuated by the propelling gases, and the piston actuated means bearing against a portion of the disk which is substantially diametrically opposite to the portion engaging the lug.

6. In a fuze for projectiles, a housing having a central axial bore opening through the forward wall of said housing, a firing pin slidably in said housing from a first safe position to a second firing position, a wire having a straight shank anchored in said housing and a hooked end extending inwardly into said bore in the path of said firing pin to retain the same in first position, a tube, said housing being rigidly mounted in and sealing, the forward end of said tube, a piston slidably in said tube, and means engaging the inner periphery of the bowed portion of the

hooked end and responsive to movement of said piston engendered by gas pressure, to cam said hooked end out of the path of said firing pin.

7. In a fuze for a projectile, a housing having a central axial bore opening through the forward wall of said housing, a firing pin slidably in said bore from a rearward safe position to a forward firing position, a retaining member mounted in a transverse aperture in said housing and having one end normally extending into said bore in the path of said firing pin to retain said firing pin in safe position, a tube, said housing being secured to and sealing the forward end of said tube, a piston slidably mounted in said tube, a plunger slidably mounted in a second bore in said housing, said second bore being parallel with and offset from said first bore, and intersecting said aperture and opening through the rear wall of said housing, said plunger being operable by said piston as the latter is moved in response to gas pressure in said tube rearwardly of said piston, the forward end of said plunger being operable to cam said retaining member out of the path of said firing pin when moved forwardly by said piston whereby said firing pin is freed for forward movement to firing position.

8. A fuze as recited in claim 7, a sleeve fitting

said tube and having its rear end flanged inwardly, said piston comprising a disk within said sleeve and normally sealing on said flange to close the opening formed thereby, a fulcrum lug extending inwardly from said sleeve, said disk engaging said plunger at a point diametrically opposite from said lug, said disk pivoting about said lug in response to gas pressure in said tube.
